UNITED STATES PATENT OFFICE

DONALD S. BARROWS, OF ROCHESTER, NEW YORK

ADJUSTABLE PIPE ORGAN VALVE

Application filed October 26, 1928. Serial No. 315,223.

The invention relates to pipe organs and has special reference to the valve mechanism embodied therein for controlling the passage of air to the pipes.

5 The principal object of the invention, generally stated, is to provide a valve which may be easily adjusted from the outside of the wind chest without it being necessary to disturb the top or bottom boards thereof, or in 10 fact other parts.

It is well known that in the ordinary construction whenever it is desired to adjust or regulate the valves it is necessary to remove either the top or bottom board of the 15 wind chest, make an adjustment and then replace the removed board before the new adjustment can be tested, or else the chest must be large enough and provided with suitable openings with air tight closures so that 20 access can be had to the interior for inspection, adjustment or replacement of the valve mechanism. In some instances this must be done several times before the desired regulation is obtained and the work is tedious, 25 expensive, more or less inaccurate and consequently only half performed in many instances so that perfectly satisfactory results are not had.

It is with the above facts in view that I 30 have devised the present invention which contemplates providing a valve construction of such character that any single valve, or as many as may be desired, can be very quickly and easily adjusted from the outside of the 35 wind chest without disturbing any of the other valves.

Another important object is to provide an 40 organ valve having means whereby the air pressure within a valve chamber may be exhausted or reduced locally, for testing purposes, without it being necessary to press any of the manual keys on the organ when it is desired to ascertain whether the corresponding pipe is working properly.

45 Another object of the invention is to provide a valve having these general characteristics and which may be used equally well in the so-called unit chest in which each valve has its own magnet energized from the corresponding manual key contact.

Still another object of the invention is to provide a valve of this character which will be simple and inexpensive to manufacture and install, easy to adjust, positive in action, efficient and durable in service, and a general 55 improvement in the art.

To the attainment of the foregoing and other objects and advantages, the invention preferably consists in the details of construction and the arrangement and combination of parts to be hereinafter more fully 60 described and claimed, and illustrated in the accompanying drawings in which:

Figure 1 is a sectional view taken through a portion of a wind chest, showing the organ pipe foot and control valve in position, parts of the latter being in elevation, 65

Figure 1^a is a sectional view showing a slight modification,

Figure 2 is a fragmentary sectional view 70 showing a slight modification of the adjusting means or valve mounting,

Figure 3 is a detail end view of the tube shown in Figure 2,

Figure 4 is a sectional view showing the invention as carried out in connection with a valve structure of the so-called unit chest, 75

Figure 5 is a view similar to Figure 1 showing a construction wherein the valve is bodily removable,

Figure 6 is a bottom plan view of the bottom board of the wind chest showing the removable plug member.

Referring more particularly to the drawings, the numeral 1 designates the interior of 80 a wind chest of a typical variety and which is ordinarily a hollow, rectangular air tight box having sides, ends and top and bottom boards, only the latter of which are shown. The top board 2 is formed with holes 3 which receive the feet 4 of the organ pipes and which permit air to enter these pipes. The bottom board 5 is formed with grooves or 85 channels 6 intersecting holes 7 which are arranged coaxially with respect to or in alignment with the holes 3.

The valve proper or valve element which coacts with the opening 3 is ordinarily a laminated disk 8, usually built up with a top 90 surface of soft leather and an intermediate 95

layer of felt or elastic medium backed by a disk of fiber or other suitable rigid material. However, these details may readily be varied as they do not constitute the essence of the invention. The valve element 8 is attached, as by a rivet 9, or other similar means, to a membrane or diaphragm 10 of skin or other flexible air tight material, a washer 11 being preferably interposed between. This membrane is stretched with the desired tension over the mouth of a cup 12, the edge being cemented thereto and preferably also secured by means of a telescoping retaining ring 13. The cup 12 may either be formed upon or suitably fastened to a hollow stem or tube 14, the bottom central portion having a depression 15 forming a seat for a spring 16. This depressed portion or downward extension is apertured at 17 so as to allow free passage of air between the tube and the cup. To avoid direct contact of the spring with the membrane 10, the latter has affixed to its underside a suitable spring cap 18 which may form also a depending apron 18^a with soft washer 18^b below to limit downward movement of valve by predetermined contact with cap as shown in Figure 1.

The lower end of the hollow stem or tube 14 is threaded, as at 19, so that it may be screwed into the holes 7 in the bottom board 5, an elastic air tight packing medium or bushing being provided if necessary. The threaded lower end of the tube is provided with any desired number of perforations 21 within the grooves 6 so as to establish communication between the same and the interior of the tube and cup 12. The tube is preferably of sufficient length to project through and beyond the bottom board 5 and it is preferable that the extremity of the tube be formed with a portion 22 of square or other angular shape to facilitate rotation by means of a suitable tool. It might also be well to provide a lock nut 23 and packing washer 24 upon the threaded end of the tube and engaging against the underside of the bottom board to prevent accidental rotation of the tube. It is intended that the lower end of the tube be formed with an opening 25 closed by means of a removable screw 26, or other equivalent device, provided for a purpose to be described.

In the operation of this form of the device, the chamber 1 is filled with air at a definite pressure above that of the atmosphere whenever the stop or rank of pipes communicating with this chamber is "on" or "drawn". Through the operation of a suitable conventional primary chest, not shown as forming no part of the present invention, the grooves or channels 6 are also filled with air preferably at the same pressure as that within the wind chest. Owing to the provision of the holes 21 which establish communication between the grooves and the cup 12, the pressure

on both sides of the diaphragm or membrane 10 is substantially uniform and the valve element 8 is held against the pipe hole 3 by the force of the spring 16. When a certain note is to be played, the depression of the corresponding manual key operates the appropriate primary valve, not shown, and the pressure air within the groove 6 is allowed to exhaust into the atmosphere, and the air pressure within the cup 12 and tube 14 likewise permitted to exhaust. The total pressure upon the exposed upper surface of the diaphragm or member 10 then exceeds the pressure exerted by the spring 16, and the diaphragm is forced downwardly, drawing the valve element 8 away from the pipe hole 3 and permitting air under pressure in the wind chest to enter the pipe foot 4, causing the pipe to sound. When the manual key is released, the exhaust opening, not shown, from the groove 6 is closed and air under pressure is caused to flow into the groove 6, filling the tube 14 and cup 12 so as to reestablish the equilibrium of the diaphragm 10, whereupon the spring 16 will return the valve 8 to its closed position, cutting the air supply to the pipe foot. In valve chests in which the valve is controlled as to closing by high pressure air independent of the air within the wind chest the spring or springs may be omitted since the excess air pressure will hold the valve closed.

In Figures 2 and 3 I have illustrated an alternative construction wherein the valve tube is not threaded through the bottom board but is differently mounted in a manner to be described. Referring to these figures in detail, it should of course be understood that the same valve member 8, diaphragm or membrane and associated parts are provided as in the first described form, all of these being mounted upon the tube 27 which corresponds to the tube 14. In this form the holes 28 in the bottom board are of larger diameter than the holes 7 so as to receive the vertical flanges 29 and 30 of upper and lower fittings 31 and 32 respectively, the former of which is located within the wind chest and the latter of which is located beneath the bottom board. In both instances it may be preferable to provide packing gaskets 33 between the fittings and the bottom board and it will be clear that any suitable securing means, such as wood screws or the like 34, may be provided for effecting secure mounting. The fitting 31 has a bore 35 therein slidably and rotatably receiving the tube 27 and, if desired, an elastic air tight packing 36 may be provided in a pocket 37 in this bore. The lower end of the tube 27 is reduced and threaded as at 38 for screwing engagement within a threaded bore 39 in the fitting 32. The lower extremity of the tube is intended to be engageable by a suitable tool for effecting turning movement and to accomplish this I preferably provide notches 40

which may receive the end of a screw driver or the like. To establish communication between the grooves 6 and the tube 27, the fitting 32 may be formed with a chamber 41 from which lead a plurality of channels or passages 42 which communicate with the grooves 6. The bore 39 extends clear to the lower end of the fitting 32 and is intended to be closed by some easily removable means such as a cap or the screw 43.

The general operation of this second described form of the invention is the same as that of the first. The difference lies in the mode of adjustment of the tube 27, it being necessary in this form to remove the screw or cap 43 to permit insertion of a screw driver or the like into the bore 39 so as to engage the notches 40 so that the tube may be turned in the proper direction. The only other difference is that the air instead of passing directly from the grooves 6 into a perforation in the tube must pass through the passages 42 into the chamber 41 and thence into the tube.

In the form of the invention shown in Figure 4, I have illustrated the valve as employed in conjunction with the so-called unit chest. In this form the previously described grooves 6 in the bottom board are omitted and each valve has its own magnet energized from the manual key contact. Referring to this figure in detail, the bottom board is shown as provided with openings 44 and 45, the former of which corresponds to the holes 7 or 28 described in connection with the other forms. In this instance I provide a supporting body or fitting 46 which may conveniently be formed as a casting and which includes an upstanding tubular portion 47 and a base or attaching portion 48. At the juncture of the tubular portion with the attaching portion the body is enlarged at 49 to be received within the opening 44 and to prevent air leakage it is preferable to provide a gasket 50 between the plate portion and the underside of the bottom board. Any suitable securing means, such as wood screws 51, may be provided for holding this body member or casting in place. The tubular portion 47 has a bore 52, the lower end portion of which is threaded at 53, and this bore receives the tube 54 which corresponds to and acts in the same capacity as the tubes 14 and 27. To make an air tight joint I may provide a packing 55 held in place by a gland 56 as clearly shown. The bore 53 extends clear to the bottom of the body member or casting and is normally closed by a screw, or the like, indicated at 57, this screw corresponding to the screws 26 and 43. Upon removal of this screw access may be had to the bore 53 for the purpose of inserting a screw driver or the like to engage within suitable notches 58 in the lower end of the tube 54, these notches corresponding to

the notches 40 in the second described form of the invention.

Located within the opening 45 is the actuating magnet 59 insulated from and carried by the plate portion 48 of the casting. The casting or body is formed with a chamber 60 beneath the poles of the magnet and this chamber communicates through a passage 61 with the bore 53 which is preferably somewhat enlarged at its intermediate portion into a chamber 62, and the chamber 60 communicates with the opening 45 through a port 63. A removable cover plate 64 covers the chamber 60 and is formed with an exhaust opening 65. An armature 66 is located within the chamber 60 and normally seats upon and closes the opening 65 though it is mounted in such manner that when attracted by the magnet 59 it will close the port 63.

In the operation of this form, it will be understood that the air pressure within the chest and beneath the diaphragm of the valve which is carried by the tube 54 is normally the same so that the valve remains closed. When the electro-magnet 59 is energized by depression of a manual key, the armature 66 will be attracted and will close the port 63 while opening the port 65. Air pressure within the tube 54 will then escape through the bore 53, chamber 62, passage 61, into the chamber 60 and out to the atmosphere through the port 65. The reduction in air pressure beneath the diaphragm of the valve will cause the diaphragm to be forced downwardly by the pressure within the wind chest, as described in connection with the first form of the invention and the valve opens, permitting the pressure air within the wind chest to pass out through the pipe foot so that the pipe will be sounded. When the electro-magnet is subsequently deenergized by the player's releasing the manual keys the armature 66 will drop, uncovering the port 63 and closing the port 65, whereupon the pressure air in the wind chest acting through the opening 45, port 63, chamber 60, passage 61, chamber 62, bore 53, tube 54, and the chamber or cup beneath the diaphragm, will equalize the pressure on the latter, thereby permitting the spring, described in the first form of the invention, to reseat the valve. The valve itself and diaphragm structure are not shown in Figure 4, nor in Figure 2 for that matter, as they are adequately illustrated in Figure 1.

Adjustment of the valve is effected in the structure shown in Figure 4 in identically the same manner as in Figure 2, that is by removing the cap or screw 57 and inserting a screw driver into the notches 58 so that the tube 54 may be turned in one direction or the other to obtain the desired adjustment. In the form shown in Figures 2 and 4 it is apparent that the pipe will sound as long as the screw 43 or 57 is out, provided the air

pressure within the wind chest is maintained in excess of the pressure of the spring beneath the diaphragm or membrane and it is therefore readily possible for the organist or organ mechanic to test the results of the regulation of the valve. In connection with the form of the invention shown in Figure 1 it is clear that by removing the screw 26 the constant sounding of the pipe may be had while the tube 14 is rotated. However, in connection with the form shown in Figure 1 it is possible to carry on the adjusting operation in a slightly different manner in that a tentative adjustment may be made by turning the tube while the screw 26 is in place, or the screw may be removed and a finger held over the orifice 25 to keep the valve closed as described above. In this way the orifice 25 is simply a test opening and it is clear that in case of a large number of pipes the provision of such a test opening in connection with each will effect a great saving in time as it obviates the necessity for depressing any of the manual keys to test the speed of the valve action.

In Figures 5 and 6 I have illustrated a modified form of the invention in which the construction is such that the valve may be bodily removed in addition to being adjusted. In this form, the valve structure itself is identically the same as disclosed in Figure 1, the only difference being that a hand hole 70 is provided in the bottom board of the wind chest, this hand hole receiving a plug-like member 71 which is apertured and provided with bushings 72 and 72^a corresponding to the bushings 7 of the first described form, the bushing 72^a being threaded for the reception of the threaded lower end of the valve tube 14. It is unnecessary to thread the bushing 72 or the coacting part of the tube. In every other respect the construction is identically the same. It is of course apparent that the plug-like member 71 must be of hollow formation and provided with ports 73 in order to establish communication between the passages 6 and the interior of the tube 14. To prevent leakage it is advisable to provide a gasket 74 about the plug-like member 71 which may very conveniently be of general frusto-conical shape and urged to its seat by some suitable means such for example as the screws 75 passing through a flange 76 or the like projecting from the bottom of the member 71 and overlapping the hand hole 70 as shown. By this particular construction it will be seen that in case it is necessary or desirable, by removing the screws 75 from the flange 76, the plug-like member 71 may be removed bodily, carrying with it the tube 14 and the valve structure comprised by the parts 8 to 18. In every other respect the action and operation are identically the same as described in connection with Figure 1. Of course the great advantage is that in case of necessity the plug member 71 may be taken

out so that the entire valve structure may be removed without disturbing the top board of the chest.

From the foregoing description and a study of the drawings it will be apparent that in all forms of the invention I have provided a very simple valve construction and one in which all the necessary adjustments may be effected from the exterior of the wind chest. It will be observed that the same general plan may be followed out in different types of actions and regardless of whether there be the unit chest arrangement or not. It is believed that the construction, operation and advantages will be readily apparent to one skilled in the art without further explanation.

While I have shown and described preferred embodiments of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. A valve for controlling communication between an organ wind chest and a pipe mounted thereon, the wind chest having a hole leading to the pipe, said valve comprising a tubular member carrying a chamber, a diaphragm covering the chamber, a valve element connected with the diaphragm and adapted to cover or uncover said hole, means for establishing communication between the interior of the tubular member and the atmosphere, and means operable from the exterior of the wind chest for adjusting said tubular member and consequently the valve element.

2. A valve for controlling communication between an organ wind chest and a pipe mounted thereon, the wind chest having a hole leading to the pipe, said valve comprising a tubular member carrying a chamber, a diaphragm covering the chamber, a valve element connected with the diaphragm and adapted to cover or uncover said hole, means for establishing communication between the interior of the tubular member and the atmosphere, and screw means operable from the exterior of the wind chest for adjusting said tubular member and consequently the valve element.

3. A valve for controlling communication between an organ wind chest and a pipe mounted thereon, the wind chest having a hole leading to the pipe, said valve comprising a tubular member carrying a chamber, a diaphragm covering the chamber, a valve element connected with the diaphragm and adapted to cover or un-

- cover said hole, means for establishing communication between the interior of the tubular member and the atmosphere, means operable from the exterior of the wind chest for adjusting said tubular member and consequently the valve element, and a spring co-operating with the diaphragm for normally holding the valve element seated over said hole when the pressure at both sides of the diaphragm is balanced. 70
4. A valve for controlling communication between an organ wind chest and a pipe mounted thereon, the wind chest having a hole leading to the pipe, said valve comprising a tubular member carrying a chamber, a diaphragm covering the chamber, a valve element connected with the diaphragm and adapted to cover or uncover said hole, means for establishing communication between the interior of the tubular member and the atmosphere, means operable from the exterior of the wind chest for adjusting said tubular member and consequently the valve element, and means other than said communication establishing means for permitting exhaust of air within the tubular member and diaphragm chamber. 75
5. In combination with an organ wind chest having top and bottom boards with the former provided with a hole receiving the foot of a pipe, a valve structure involving a member rotatably mounted in said bottom board and a diaphragm actuated valve element carried by the upper end of the said member for covering or uncovering said hole, and means for adjusting the valve structure from the exterior of the bottom board. 80
6. In a pipe organ having a wind chest with top and bottom boards, the former being provided with a hole receiving the foot of a pipe, a valve mechanism for controlling communication between the wind chest and pipe, said mechanism comprising a tubular member rotatably mounted in said bottom board, and means for adjusting said valve mechanism from beneath the bottom board while the top and bottom boards and the valve mechanism remain in situ. 85
7. In a pipe organ having a wind chest with top and bottom boards, the former being provided with a hole receiving the foot of a pipe, a valve mechanism for controlling communication between the wind chest and pipe, said mechanism involving a member rotatably mounted in said bottom board, means for adjusting said valve mechanism from beneath the bottom board while the top and bottom boards and the valve mechanism remain in situ, and means arranged locally on the valve mechanism whereby the valve may be opened or closed without actuation of a manual key corresponding to the pipe. 90
8. In an organ having a wind chest with top and bottom boards, the former having a hole receiving the foot of a pipe, a valve mechanism for controlling communication between the wind chest and the pipe, the valve mechanism extending through the wind chest and embodying a tubular member carrying a chamber covered by a membrane, a valve element carried by the membrane and movable therewith for covering and uncovering said hole, means holding said valve element normally seated over the hole when the air pressure is balanced at both sides of the membrane, the air within the tubular member being adapted to be exhausted into the atmosphere upon actuation of a manual key corresponding to the pipe, and screw means at the bottom board of the wind chest operable to move said tubular member longitudinally for regulating the position of the valve element without disturbing any part of the wind chest. 95
9. In an organ having a wind chest with top and bottom boards, the former having a hole receiving the foot of a pipe, a valve mechanism for controlling communication between the wind chest and the pipe, the valve mechanism extending through the wind chest and embodying a tubular member carrying a chamber covered by a membrane, a valve element carried by the membrane and movable therewith for covering and uncovering said hole, means holding said valve element normally seated over the hole when the air pressure is balanced at both sides of the membrane, the air within the tubular member being adapted to be exhausted into the atmosphere upon actuation of a manual key corresponding to the pipe, screw means at the bottom board of the wind chest operable to move said tubular member longitudinally for regulating the position of the valve element without disturbing any part of the wind chest. 100
10. In an organ having a wind chest with top and bottom boards, the former having a hole receiving the foot of a pipe, a valve mechanism for controlling communication between the wind chest and the pipe, the valve mechanism extending through the wind chest and embodying a tubular member carrying a chamber covered by a membrane, a valve element carried by the membrane and movable therewith for covering and uncovering said hole, means holding said valve element normally seated over the hole when the air pressure is balanced at both sides of the membrane, the air within the tubular member being adapted to be exhausted into the atmosphere upon actuation of a manual key corresponding to the pipe, screw means at the bottom board of the wind chest operable to move said tubular member longitudinally for regulating the position of the valve element without disturbing any part of the wind chest, the valve mechanism having an opening at its lower end adapted to establish communication with the atmosphere, and means normally closing said opening. 105
11. In an organ having a wind chest with top and bottom boards, the former having a hole receiving the foot of a pipe, a valve mechanism for controlling communication between the wind chest and the pipe, the valve mechanism extending through the wind chest and embodying a tubular member carrying a chamber covered by a membrane, a valve element carried by the membrane and movable therewith for covering and uncovering said hole, means holding said valve element normally seated over the hole when the air pressure is balanced at both sides of the membrane, the air within the tubular member being adapted to be exhausted into the atmosphere upon actuation of a manual key corresponding to the pipe, screw means at the bottom board of the wind chest operable to move said tubular member longitudinally for regulating the position of the valve element without disturbing any part of the wind chest. 110
12. In an organ having a wind chest with top and bottom boards, the former having a hole receiving the foot of a pipe, a valve mechanism for controlling communication between the wind chest and the pipe, the valve mechanism extending through the wind chest and embodying a tubular member carrying a chamber covered by a membrane, a valve element carried by the membrane and movable therewith for covering and uncovering said hole, means holding said valve element normally seated over the hole when the air pressure is balanced at both sides of the membrane, the air within the tubular member being adapted to be exhausted into the atmosphere upon actuation of a manual key corresponding to the pipe, screw means at the bottom board of the wind chest operable to move said tubular member longitudinally for regulating the position of the valve element without disturbing any part of the wind chest. 115
13. In an organ having a wind chest with top and bottom boards, the former having a hole receiving the foot of a pipe, a valve mechanism for controlling communication between the wind chest and the pipe, the valve mechanism extending through the wind chest and embodying a tubular member carrying a chamber covered by a membrane, a valve element carried by the membrane and movable therewith for covering and uncovering said hole, means holding said valve element normally seated over the hole when the air pressure is balanced at both sides of the membrane, the air within the tubular member being adapted to be exhausted into the atmosphere upon actuation of a manual key corresponding to the pipe, screw means at the bottom board of the wind chest operable to move said tubular member longitudinally for regulating the position of the valve element without disturbing any part of the wind chest. 120
14. In an organ having a wind chest with top and bottom boards, the former having a hole receiving the foot of a pipe, a valve mechanism for controlling communication between the wind chest and the pipe, the valve mechanism extending through the wind chest and embodying a tubular member carrying a chamber covered by a membrane, a valve element carried by the membrane and movable therewith for covering and uncovering said hole, means holding said valve element normally seated over the hole when the air pressure is balanced at both sides of the membrane, the air within the tubular member being adapted to be exhausted into the atmosphere upon actuation of a manual key corresponding to the pipe, screw means at the bottom board of the wind chest operable to move said tubular member longitudinally for regulating the position of the valve element without disturbing any part of the wind chest. 125
15. In an organ having a wind chest with top and bottom boards, the former having a hole receiving the foot of a pipe, a valve mechanism for controlling communication between the wind chest and the pipe, the valve mechanism extending through the wind chest and embodying a tubular member carrying a chamber covered by a membrane, a valve element carried by the membrane and movable therewith for covering and uncovering said hole, means holding said valve element normally seated over the hole when the air pressure is balanced at both sides of the membrane, the air within the tubular member being adapted to be exhausted into the atmosphere upon actuation of a manual key corresponding to the pipe, screw means at the bottom board of the wind chest operable to move said tubular member longitudinally for regulating the position of the valve element without disturbing any part of the wind chest. 130

regulating the position of the valve element without disturbing any part of the wind chest, and sealing means engaging the tubular member for preventing leakage of air

5 thereabout.

11. In an organ having a wind chest with top and bottom boards, the former having a hole receiving the foot of a pipe, a valve mechanism for controlling communication
- 10 between the wind chest and the pipe, comprising a unitary structure including a tubular member having an enlargement at its upper end constituting a diaphragm chamber, a membrane stretched across said chamber
- 15 and carrying a valve element adapted to cover or uncover said hole, a spring mounted within the chamber and urging the membrane into a position holding the valve element in closed position, and means operable
- 20 from beneath the bottom board for moving the tubular member longitudinally and adjusting the position of the valve element.

12. In an organ having a wind chest with top and bottom boards, the former having a
- 25 hole receiving the foot of a pipe, a valve mechanism for controlling communication between the wind chest and the pipe, comprising a unitary structure including a tubular member having an enlargement at its upper
- 30 end constituting a diaphragm chamber, a membrane stretched across said chamber and carrying a valve element adapted to cover or uncover said hole, a spring mounted within the chamber and urging the membrane
- 35 into a position holding the valve element in closed position, means operable from beneath the bottom board for moving the tubular member longitudinally and adjusting the position of the valve element, and means irre-
- 40 spective of manual key operated means for exhausting the pressure within the tubular member to effect unseating of the valve element and communication between the wind chest and the pipe.

- 45 13. In a pipe organ having a wind chest including top and bottom boards, the former being apertured and carrying the foot of a pipe at the aperture, the bottom board being formed with an opening concentric with said
- 50 aperture, a removable plug member mounted within said opening and having a central hole in axial relation to said aperture, a valve structure carried by said plug member for controlling communication between the in-
- 55 terior of the wind chest and said aperture, said structure involving a tubular member mounted in the hole of said plug and means whereby the valve structure may be adjusted with respect to said plug member.

60 In testimony whereof I affix my signature.
DONALD S. BARROWS.
